Primary Examiner — Rosemary K Tarcza*Assistant Examiner* — Yolanda Robinson(74) *Attorney, Agent, or Firm* — Birch, Stewart, Kolasch & Birch, LLP(57) **CLAIM**

I claim the ornamental design for a washing machine tub, as shown and described.

DESCRIPTION

FIG. 1 is a perspective view of washing machine tub showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and

FIG. 7 is a bottom plan view thereof; and

FIG. 8 is an exploded perspective view thereof; and,

FIG. 9 is a perspective view showing an illustration of use thereof.

The dash-dot broken lines represent unclaimed portions of the washing machine tub and form no part of the claimed design.
